(57) **CLAIM**

The ornamental design for a freight railroad car reflector, as shown and described.

DESCRIPTION

This application relates to the following co-pending commonly owned patent applications: "Freight Railroad Car Reflector," Ser. No. 11/277,216; and "Freight Railroad Car Reflector," Ser. No. 29/246,211.

FIG. 1 is a front perspective view of one embodiment of the freight railroad car reflector showing our new design;

FIG. 2 is a rear perspective view of FIG. 1;

FIG. 3 is a front view of FIG. 1;

FIG. 4 is a rear view of FIG. 1;

FIG. 5 is a top plan view of FIG. 1;

FIG. 6 is a bottom plan view of FIG. 1;

FIG. 7 is a left side elevation view of FIG. 1, the right side being a mirror image;

FIG. 8 is a front perspective view of a modified embodiment;

FIG. 9 is a rear perspective view of FIG. 8;

FIG. 10 is a front view of FIG. 8;

FIG. 11 is a rear view of FIG. 8;

FIG. 12 is a top plan view of FIG. 8;

FIG. 13 is a bottom plan view of FIG. 8; and,

FIG. 14 is a left side elevation view of FIG. 8 the right side being a mirror image.

The broken line(s) which define the bounds of the claimed design form no part thereof.
